FOLDING BRAKE

Oscar G. Lilja, Rockford, Ill.

Application June 24, 1940, Serial No. 342,116

8 Claims. (Cl. 153—16)

This invention relates to bending machines and particularly to sheet metal bending machines of the so-called brake-type such as are commonly used in sheet metal shops for the purpose of bending relatively thin section sheet metal.

The difficulty with these devices in the past has been the limitation in their ability to bend the metal through much more than the right angle. So far as I am aware, none of these machines have been capable of bending the metal back upon itself in the manner required for the production of a satisfactory sheet metal fold. The common practice has been to bend the edge portion of the metal through slightly more than 90° by means of the brake, and to thereafter manually hammer the edge portion down to bend it through substantially 180°.

An important object of the invention is the provision of a folding brake capable of bending the metal through substantially 180° so as to complete the full bend with a single operation.

A further object of the invention is the provision of a brake-type bending device in which the upper bending form is retractable, and wherein means are provided for retracting this member after the bend has been partially formed to permit the completion of the bending in a single operation.

A still further object of the invention is the provision of a bending brake in which the sheet metal is rigidly held in position during the bending operation, and wherein latch means serve to hold the apron in position through a substantial portion of the bending operation and is released toward the end of the bend for the purpose of permitting the return of the apron to inoperation position.

A further object of the invention is the provision of a brake wherein the apron is supported in a novel fashion, and additional means are provided for holding the metal in place.

Other objects and advantages will appear from the following description and the accompanying drawings, in which—

Figure 1 is a side elevation of a brake embodying my invention showing the apron and apron frame in the open position;

Fig. 2 is a section on the line 2—2 of Figure 1, showing the parts in the same position, a sheet of metal being positioned on the table and bed in position for the start of the bending operation;

Fig. 3 is a section on the line 3—3 of Figure 1 showing the apron and frame in the lower bending position;

Fig. 4 is a section similar to Fig. 2 showing the

parts in the third step of the bending operation, the metal being bent through somewhat more than 90° and substantially at the start of the tripping operation;

5 Fig. 5 is a view similar to Fig. 2 showing the parts in the positions occupied thereby at the conclusion of the bending operation, the edge portion of the metal being bent through substantially 180°, and the apron being retracted to its inoperative position;

Fig. 6 is a section on the line 6—6 of Fig. 4, and Fig. 7 is a section on the line 7—7 of Fig. 4.

The embodiment of the invention herein described has a supporting frame or tail comprising legs at opposite ends thereof designated generally by the numerals 8 and 9, and top and side rails 11 and 12 at the back side and ends thereof. Other conventional frame members, such as shown at 13, are provided as required, to give rigidity to the table. Positioned at the ends of the supporting structure above the legs 8 and 9 are end plates 14 and 15 formed of heavy section cast metal as best shown in Figs. 1 and 3. These end plates are connected at the rear by a channel iron member 16 for the purpose of rigidly interconnecting the end plates. The end plates and the channel iron member 16 are fastened to the top of the supporting table in any well known manner, as, for example, by bolting or welding so as to be fixedly supported thereon. Flanges 17 and 18 are provided adjacent the forward edges of the plates 14 and 15 and project laterally therefrom, as best shown in Figs. 1 and 3, these flanges being provided with internally threaded holes 19, and with a forwardly disposed lug 21 provided with an internally threaded opening carrying a threaded screw 22. Positioned against the flanges 17 and 18 and spanning the distance between the plates 14 and 15 is a bed designated generally by the numeral 23 in the form of a relatively thick plate. This plate is provided adjacent each end with elongated openings 24 for the reception of screws 25 and 26 adapted to engage in the threaded openings 19 to retain the bed in position. The elongated openings 24 permit of adjustment of the elevation of the bed by action of the screws 22 so that the position of the upper edge of the plate can be adjusted and the screws 25 and 26 drawn tight in order to accommodate the brake to metals of relatively great thickness. Positioned on the upper edge of the member 16 and extending forwardly to the bed 23 is a table 27, the table having support on the member 16 and on the bed, the upper surface thereof being flush with the upper end of the bed plate 23, as

best shown in Fig. 2. The table 27 terminates short of the end plates 14 and 15, as will be seen from Fig. 3, to provide space through which various operating elements may pass, as will presently be described.

The forward edge of the end plates 14 and 15 has bosses 28 and 29 adapted to support pivot members 31 and 32 (Figure 1) for rotation on a horizontal axis by means of pivot pins passing through the bosses 28 and 29 and through ears 33 on the pivot member 31 and ears 34 on the pivot member 32. These pivot members form the end portions of a bending leaf designated generally by the numeral 35 which has a bending plate 36 attached at its ends to the pivot members 31 and 32 by means of screws 37 and 38 passing through elongated openings 39 and 41 in the plate 36 and threaded into openings in the pivot members. The pivot members have laterally disposed flanges 42 carrying screws 43 adapted to adjust the position of the plate 36 on the pivot members, as will be apparent from Fig. 3. The bending leaf is so arranged that the upper edge of the bending plate 36 is normally coplanar with the upper edge of the bed plate 23 in the manner shown in Fig. 2, whereby these plates, together with the table 27, function to support a piece of sheet metal as shown at 44 for the purpose of bending the same in the general manner of a conventional brake. The upper forward edge of the plate 23 and the upper rear edge of the leaf 36 are substantially on the center line of the pivots on which the leaf turns, so that when the leaf is rotated through 180°, the leaf will rest substantially in the same plane as the bed, as shown in Fig. 5.

For the purpose of bracing and stiffening the bed plate 23 and the bending leaf plate 36, these plates are each provided with a stiffening rib as shown at 45 extending longitudinally thereof and bracing arms 46 and 47 extending from the plates in the form of a V, and having a brace rod 48 connecting the lower edges of the plates with the apex of the V, as shown at 49 (Figure 1).

Arms 51 and 52 are attached to the pivot members 31 and 32 and project upwardly and outwardly, as best shown in Figs. 1 and 3 when the bending leaf occupies its lower position, the arms carrying weights 53 and 54 for the purpose of counterbalancing the weight of the bending leaf and for assisting in the application of pressure during the bending operation. These weights also serve to facilitate the production of what might be called a hammer blow to the folded metal at the close of the bending operation, this being accomplished by the operator rotating the leaf backward slightly and releasing the same, so that the weights force the leaf back into contact with the metal.

Rotatably carried between the end plates 14 and 15 is an apron frame designated generally by the numeral 55. This frame includes guide plates 56 at each end thereof, each of which has a slot 57 adapted for rotatable reception on a cap screw 58 for rotation of the guide plates on the end plates 14 and 15. The guide plates are connected by means of a crossbar 59 attached to the guide plates by screws 61 (Fig. 3) which bar serves to rigidly interconnect the two plates to cause the same to rotate on the cap screws 58 as a unit. Each of the guide plates has a groove 62 provided by shoulders 63 and 64, the groove being adapted for reception of the ends of an apron designated generally by the numeral 65, the apron being supported therein for sliding movement in the

grooves 62 between the positions shown in Figs. 2, 3 and 4 and the position shown in Fig. 5, the apron being normally biased to the position shown in Fig. 5 by means of springs 66 having one end anchored to the apron by means of screws 67, and the opposite end anchored to the crossbar 59 as shown at 68 (Figs. 2 and 5).

The apron is moved from its inoperative or retracted position as shown in Fig. 5 to its operative position as shown in Figs. 2-4 by means of spaced levers 69 and 71 pinned to a cross shaft 72, which shaft has pivotal support in ears 73 on the guide plates 56. The levers 69 and 71 are connected by means of links 74 to upstanding bosses 75 on the upper surface of the apron so that by rotating the levers to the position shown in Fig. 2 the apron is moved from the position of Fig. 5 to the position of Fig. 2. The apron is held in the operative position of Figs. 2-4 by means of a latch having a latch bar 76 (Figs. 3, 4 and 5) provided with a hooked end having an adjusting screw 70 adapted to engage over the back of the apron as shown in Figs. 3 and 4, the latch bars being pivotally supported on the shoulders 63 by means of cap screws 71 and being urged to the engaged position by means of springs 78. The screws 70 serve to permit adjustment of the operative position of the apron for different thicknesses of metal. Associated with each of the latch bars is a releasing dog 79 pivotally supported on the shoulders 63 by means of cap screws 81, the dogs also being normally urged to the position shown in Fig. 3 by means of the spring 78. These dogs have an end 82 bearing against an outwardly disposed end 83 of the latch bar 76 so arranged that when the dogs are rotated in a counterclockwise direction facing Fig. 3, the end 82 urges the end portion 83 of the latch bar in a clockwise direction, thus releasing the bar from the apron and allowing the apron to be moved to the retracted position under the action of the springs 66. Pins 84 are provided on each of the dogs positioned to be engaged by the outer surface of the bending leaf, as best shown in Fig. 4, for the purpose of releasing the apron when the bending operation proceeds to the required point. The screws 84 are adjustable so as to adjust the point at which the apron will be withdrawn.

The apron frame 55 is rotatable between the position shown in Fig. 2 and that of Fig. 3 and is normally urged to the open position of Fig. 2 by means of springs 85 attached to bars 86 fastened to the rear ends of the shoulders 63 and 64 (Fig. 3), the opposite ends of the springs being carried on lugs 87 attached to the back side of the flanges 11 and 12. The extent of this movement is limited by levers 88 and 89 pivotally supported on the end plates 14 and 15 by means of cap screws 91, these levers being rotatable between their open position, as shown in Fig. 2, in which the frame is rotated upwardly under the action of the springs 85 and the position shown in Fig. 3 in which the frame is moved downward to the operative position with the apron 65 urged against the upper surface of the sheet metal resting on the table 27, the levers each having a cam surface as shown at 92 for rotating the apron frame against the action of the springs. A pressure bar 93 extends between the guide plates 56 in a position to contact the work when the frame occupies its lower position and has rearwardly disposed arms 94 pivotally supported on the shoulders 64 by means of cap screws 95, the bar 93 being urged to rotate in a clockwise direction

about the cap screws 95 by action of springs 96 acting between the ends of the arms 94 and the bar 59. The extent of this rotary motion is limited by stops 97 carried in the bar 59 and adjustable so as to vary the amount of this rotation under the action of the springs 96, the stops bearing against the arms 94. Thus, when the apron frame is brought to the position shown in Figs. 3 and 4, the beveled surface 98 of the pressure bar 93 first engages the work, and upon continued rotation of the frame, the beveled face 99 of the apron is brought into contact with the work, this continued movement causing stressing of the spring 96.

In operation, the sheet metal to be bent, such as that shown at 44, is placed on the table 27 with the parts in the position shown in Figs. 1 and 2, the point where the bend is to occur being placed at the junction between the bed and the bending leaf. Thereafter the levers 88 and 89 are brought to the upper position as shown in Fig. 3, bringing the pressure bar 93 and the apron 65 into contact with the metal. Thereafter the bars 46 and 47 are grasped by the operator and the bending leaf moved to the position shown in Fig. 5. During this operation the parts will pass through the position shown in Fig. 4. In other words, when the outer surface of the bending leaf contacts the screws 84, the dogs 79 will be rotated, causing the latch bars 76 to release the ends of the apron and allowing the apron to move up to the position shown in Fig. 5. It will be seen that this occurs after the edge of the metal has been bent through slightly more than 90° as shown at 101 in Fig. 4. The apron having been withdrawn from beneath the folded edge portion of the metal, continued movement of the bending leaf causes the edge portion to be folded back upon itself in the manner shown in Fig. 5. In order to further compact the folded portion, the leaf may be rotated back slightly, as, for example, to the position shown in Fig. 4, and released, whereupon it will be brought down against the folded portion with a hammer blow under the impact of the weights 53 and 54.

An important advantage accruing from the structure shown in Figs. 1-7, inclusive, is the fact that a complete folding operation can be conducted on sheet metal with a single operation of the folding leaf. In other words, the metal is inserted in the manner of a conventional sheet metal brake, and by a single operation of the bending leaf a complete fold can be produced, as distinguished from slightly more than a 90° bend, as has heretofore been possible. Another advantage of the construction lies in its ease of operation and the manner in which the apron is withdrawn during the bending operation. It will also be seen that I have provided improved means whereby the work is fixedly held in position during the bending operation.

It will be understood that the embodiment of the invention herein shown is by way of illustration and not limitation, and I do not wish to be limited except as required by the scope of the appended claims, in which—

I claim:

1. The combination in a folding brake of spaced end members, a bed extending between said end members for supporting a sheet of metal to be bent, a bending leaf rotatable about one edge from a depending vertical position to an upstanding vertical position to bend said sheet, a frame supported between said end members for rotation between a closed position engaging

said sheet and an open position, means on said frame for engaging said sheet outside the bending area thereof to clamp said sheet against movement when the frame occupies the closed position, an apron positioned on said frame movable thereon between an operative position to engage said sheet at the bending area when said frame occupies said closed position and an inoperative position, manually operative means for

10 moving said apron from inoperative to said operative position, spring means for moving said apron from said operative to said inoperative position, latch means for retaining said apron in said operative position, and means for releasing said latch at a predetermined point in the rotation of said leaf in response to rotation thereof for movement of said apron out of said operative position to withdraw said apron from the path of said leaf.

20 2. The combination in a folding brake of spaced end members, a bed extending between said end members for supporting a sheet of metal to be bent, a bending leaf rotatable to bend said sheet against said bed, a clamping frame movably supported on said end members for movement between a closed position engaging said sheet and an open position, holding means on said frame movable therewith for engaging said sheet outside the bending area thereof to clamp said sheet against movement when the frame occupies closed position, an apron positioned on said frame for movement thereon between an operative position to engage said sheet at the bending area when said frame occupies said closed position and an inoperative position, and means for moving said apron from said operative to said inoperative position in response to movement of said bending leaf through a predetermined part of its bending rotation.

30 3. The combination recited in claim 2 wherein said holding means includes means for engaging said sheet, spring means for urging the engaging means against the sheet when said frame occupies said closed position, and stop means for limiting the action of said spring means when said frame is moved to open position to lift said engaging means and release the sheet.

40 4. The combination in a folding brake of a bed for supporting a sheet of metal to be bent, a bending leaf rotatable to bend said sheet against said bed, an apron frame having spaced rotatable end plates each provided with a slide way, an apron having its ends positioned in said ways for sliding movement between operative and inoperative positions, means for rotating said frame to bring said apron into contact with the sheet on said bed when the apron occupies its operative position, and means responsive to movement of said bending leaf through an intermediate point of its rotation for moving said apron from said operative to said inoperative position out of contact with said sheet to withdraw said apron from the path of said leaf.

50 5. The combination recited in claim 4 wherein weight means is positioned on said bending leaf to resist rotation thereof during the first part of its movement and to assist rotation during the latter part of its movement to drive said leaf against the sheet on said bed and thereby facilitate the folding of the metal.

60 6. The combination in a folding brake of a bed for supporting a sheet of metal to be bent, a bending leaf rotatable to bend said sheet against said bed, clamping means for engaging said sheet outside the bending area thereof to clamp said

sheet against movement during the bending operation, an apron movable between an operative position to engage said sheet and a retracted inoperative position, latch means for retaining the apron in said operative position for bending of the sheet thereagainst in response to rotation of the leaf through a part of a rotation, spring means for urging said apron to said inoperative position, and means for releasing said latch means to move said apron out of the operative position so that upon further rotation of the leaf the sheet is bent upon itself to form a fold.

7. The combination in a folding brake of spaced end members, a bed extending between said end members for supporting a sheet of metal to be bent, a clamping frame comprising clamping means for holding said sheet in position against said bed, a movable apron against which said sheet is bent, and means for moving said apron with respect to the remainder of the clamping frame to effect a folding operation, means for supporting said clamping frame on said end members for rotation with respect thereto and removal therefrom, means carried on said end members positioned to bear against said frame

to rotate the same to a position engaging the sheet, and a bending leaf rotatable to bend said sheet against said apron and said bed.

8. The combination in a folding brake of a stationary bed for supporting a sheet of metal to be bent, a bending leaf rotatable through about 180° to bend said sheet against said bed to form a fold, clamping means for engaging said sheet outside the bending area thereof to clamp said sheet against the bed to prevent movement of the sheet during the bending operation, an apron movable between an operative position engaging said sheet at the bending area for bending of the sheet thereagainst in response to rotation of the bending leaf through a part of a rotation and a retracted inoperative position, means for moving said apron out of said operative position, and means operated by said leaf during the rotation thereof toward said apron for operating the last mentioned means to withdraw said apron from the bending area for continued movement of said leaf through substantially 180° to bend the sheet upon itself.

OSCAR G. LILJA.
